CUTTER HEAD FOR SHAVING MACHINES

Arthur G. Stevenson, Rochester, N. Y.

Application May 7, 1938, Serial No. 206,605

4 Claims. (Cl. 30—43)

This invention relates to shaving machines and has for its object to provide a novel form of cutter head for such a machine.

Another object of this invention is to provide 5 the cutter head with a novel shear-member.

A further object of this invention is to provide the cutter of the cutting head with novel cutting edges for cooperation with the shear-member.

A still further object of this invention is to 10 provide a novel construction for the drive of the shear-member.

All these and other objects and attendant 15 advantages of this invention will become more readily apparent from the detailed description thereof which follows, reference being had to the accompanying drawing in which

Figure 1 is a top plan view of the shaving machine embodying the new and improved cutter head.

20 Figure 2 is a side elevation thereof.

Figure 3 is an end elevation thereof.

Figure 4 is a detail view of the cutter member 25 of the cutter head.

Figure 5 is an end elevation of the cutter member.

Figure 6 is a longitudinal sectional view of the 30 cutter member taken on the line 6x—6x of Figure 4.

Figure 7 is a cross section of the cutter member 35 taken on the line 7x—7x of Figure 6.

Figure 8 is a detail view of the shear-member of the cutter head.

Figure 9 is an end elevation of the shear-member.

35 Figure 10 is a longitudinal sectional view of the shear-member taken on the line 10x—10x of Figure 8.

Figure 11 is a cross section of the shear-member 40 taken on the line 11x—11x of Figure 10.

Figure 12 is an enlarged cross section of the cutter head taken on the line 12x—12x of Figure 3.

Figure 13 is an enlarged longitudinal section of the cutter head taken on the line 13x—13x of Figure 3.

45 Figure 14 is an enlarged section of the cutting edges of the cutter member of the cutter head as they appear when placed against the beard for shaving.

50 In the several figures of the drawing like reference numerals indicate like parts.

The shaving machine embodying the subject matter of my present invention is provided with a suitable driving motor encased in the handle 1 55 and provided with a drive shaft 2. The latter

carries a ball member 3 which is eccentrically mounted on the tapered shank 4 to thus provide a ball crank for the operation of the cutter head as will hereinafter appear. At the outer end of the handle 1 is formed the semi-cylindrical cradle or seat 5 adapted to have the cutter head 5 removably mounted therein.

The cutter head comprises the cylindrical cutter member 6 which is provided with an eccentrically located longitudinally extending cylindrical bearing 7 in which is mounted to oscillate the shear member 8. The eccentric arrangement of the bearing 7 provides in the cylindrical cutter member at diametrically opposite sides a thin and a thick wall, of which the thin wall is longitudinally slotted and then hollow or concavely ground to provide the razor edges 9 and 10 on opposite sides of the slot.

In the thick wall of the cutter member are provided a pair of holes 11, 11 which are threaded 20 to receive suitable mounting screws 12, 12 with which the cutter head is removably mounted in the seat or cradle 5 of the handle. Extending thru the middle of the thick wall of the cutter member is a large opening 13 which is adapted to have the ball crank of the drive shaft project therethru for the engagement and operation of the shear-member 8.

The shear-member comprises a longitudinally grooved and transversely slotted cylindrical member in order to provide the wide longitudinal groove 14 for the engagement of the ball crank and the narrow groove 14A diametrically opposite to the groove 14 for the spacing of the two rows of parallel shear fingers 15, 15 which 30 are adapted to cooperate with the razor edges 35 of the cutting member. The transverse slots 16, which space the shear fingers longitudinally, are arranged so as to stagger the shear fingers in one row from the shear fingers in the other row. In this way the cooperative action of one row of 40 shear fingers with one razor edge supplements the cooperative action of the other row of shear fingers with the opposite razor edge. The hairs projecting between the cutting edges of the cutting member will thus be severed by the action 45 of a shear finger from either one or the other row of these fingers. The lateral spacing of the shear fingers together with their peripheral spacing provide a maximum unobstructed space for 50 the hairs to project into the cutting member which, with the comb effect produced by each row of shear fingers, cause the hairs to be moved into an erect position against either one or the other of the razor edges to be severed thereon 55

when the shear fingers force the hairs against them.

As illustrated in Figures 12 and 14, the cutting edges are hollow ground so as to provide a depression in the cutting member into which the skin is molded when pressed thereagainst as illustrated in Figure 14. The hairs of the skin along the middle of this molded portion may thus project into the space between the razor edges 9 and 10 and this space is wide enough so that any hair of a beard which has not been allowed to grow too long may erect itself or be moved into an erect position by the shear fingers to be forced against one or the other of the razor edges and severed thereby close to the skin.

As the cutter head is moved over the skin while being yieldingly held thereagainst small sections of the entire surface of the skin are continuously molded into the cutter head between the razor edges. This causes the hairs on the skin to yieldingly spring and project into the space between the razor edges to be forced against and severed by either one or the other of these edges on the oscillating movement of the shear fingers.

For the purpose of yieldingly holding the shear fingers against the inside of the cutter member so as to produce an efficient shearing action between them and the razor edges, an elongated spring 20 is located in the groove 14 and held against endwise movement therein by the engagement of its ends into suitable indentations 21, 21 in the shear member. The ball member 3 thus rests against and moves over this spring and thereby exerts at all times a yielding pressure against the shear member for the shearing action between it and the razor edges.

The longitudinal grooves 22, 22 which extend across the shear fingers of the shear member on substantially opposite sides thereof provide suitable space for the insertion of a cleaning rod from one end to the other of the cutter head.

The ends of the seat or cradle 5 in which the cutter head is mounted are closed by the retaining plates 23 and partially extend over the ends of the cutter head so as to hold the shear member against endwise movement therein and by removing one of these end plates the shear member may thus be removed from the cutter head for cleaning.

I claim:

1. A tubular cutter head for shaving machines having a longitudinal slot therein, a hollow ground razor edge provided on the longitudinally extending opposing edges of said slot so as to convexedly shape the skin toward said razor edges, and a shearing member mounted to oscillate in said cutter head, a longitudinal slot in said shearing member, transversely extending slots terminating from opposite sides into said longitudinal slot with the transverse slots on one side being staggered relative to the slots on the other side of said longitudinal slot to provide two rows of transversely spaced cutting fingers on said shearing member with the cutting fingers of one row being staggered relative to the cutting fingers of the other row.

2. A tubular cutter head for shaving machines having a longitudinal slot therein, a hollow ground razor edge provided on the longitudinally extending opposing edges of said slot so as to convexedly shape the skin toward the slot in the cutter head, a cylindrical shear member mounted to oscillate within said tubular cutter head, a longitudinal slot in said shear member, transverse slots extending from the sides of said shear member into said longitudinal slot, said transverse slots being arranged on opposite sides of said longitudinal slot so as to form two rows of longitudinally and circumferentially spaced shear fingers with the fingers in one row being staggered relative to the fingers in the other row.

3. A tubular cutting head as set forth in claim 2 including a second longitudinal slot in said shear member, a ball crank projecting into said second slot and a single spring member interposed between the end of said ball crank and said shear member and extending longitudinally of said second slot to yieldingly hold said shear member for shearing action with said razor edges the full length thereof on the rotation of said ball crank.

4. A tubular cutting head as set forth in claim 1 and provided with longitudinal grooves at the bottom of the two rows of shear fingers so as to receive the severed hair and permit the expulsion thereof from the shear member from the ends of the cutting head.

ARTHUR G. STEVENSON. 50
